UNITED STATES PATENT OFFICE.

HORACE E. WALKER, OF NORMAN, OKLAHOMA.

COTTON-BOLL EXTRACTOR AND COTTON-CLEANING MACHINE.

1,354,358.

Specification of Letters Patent. Patented Sept. 28, 1920.

Application filed March 10, 1920. Serial No. 364,610.

To all whom it may concern:

Be it known that I, HORACE E. WALKER, a citizen of the United States, residing at Norman, in the county of Cleveland and State 5 of Oklahoma, have invented certain new and useful Improvements in Cotton-Boll Extractors and Cotton-Cleaning Machines, of which the following is a specification, reference being had to the accompanying drawings.

This invention relates to certain improvements in cotton boll extractor and cotton cleaning machines, and it is an object of the invention to provide a novel and improved machine adapted to deliver cotton to the gin free and clear of all hulls, dirt and trash whereby the capacity of the gin is materially increased together with a decided raise in the grade of the cotton.

Another object of the invention is to provide a novel and improved machine of this general character including an air chamber into which a boll breaker delivers and wherein means are provided within said chamber to effectively pick the cotton from the trash and hulls and wherein the dirt and kindred minute particles are carried out with the air.

An additional object of the invention is to provide a novel and improved machine of this general character including means whereby the cotton, after leaving the air chamber, is subjected to a further action whereby cotton or lint is separated for delivery to the gin while the trash, bolls, and dirt are carried off.

Furthermore, it is an object of the invention to provide a novel and improved machine of this general character including an air chamber or conduit into which a boll breaker delivers and wherein a portion of the floor of said chamber or conduit constitutes the upper stretch of an endless member traveling in a direction toward the ingress end of the chamber or conduit and which member is provided with means to engage and recover the cotton, together with means arranged within the air chamber or conduit to facilitate the proper coaction of the endless member with the cotton.

A still further object of the invention is to provide a novel and improved machine of this general character including a housing into which the material recovered from within the air chamber or conduit is deliv-

ered and wherein means are arranged within said housing to effectively separate the cotton or lint from the matter foreign thereto such as bolls, trash and dirt.

It is also an object of the invention to provide a novel and improved machine of this general character wherein the separating means arranged within the housing into which the material is delivered from the air conduit or chamber comprises a rotary member 60 having its periphery provided with means to recover the cotton and lint and wherein members or beaters are provided to force the material toward the rotary member 65 to assure the desired functioning of 70 said member.

The invention consists in the details of construction and in the combination and arrangement of the several parts of my improved machine whereby certain important 75 advantages are attained and the device rendered simpler, less expensive and otherwise more convenient and advantageous for use, as will be hereinafter more fully set forth.

The novel features of my invention will 80 hereinafter be definitely claimed.

In order that my invention may be the better understood, I will now proceed to describe the same with reference to the accompanying drawings, wherein:

Figure 1 is a view in side elevation of a cotton boll extractor and cotton cleaning machine constructed in accordance with an embodiment of my invention;

Fig. 2 is a longitudinal vertical sectional view taken through the device as illustrated in Fig. 1, a second position of one of the deflectors being indicated by dotted lines and a conveyer being also indicated by dotted lines;

Fig. 3 is a fragmentary view in side elevation opposite to that illustrated in Fig. 1; and

Fig. 4 is a fragmentary transverse sectional view taken through the air chamber 100 and illustrating in detail the mounting of one of the deflectors.

As disclosed in the accompanying drawings, H denotes a housing of requisite dimensions and has one end portion of its top 105 open, as at 1, and through which discharges the endless member M arranged within the substantially horizontally disposed air chamber or conduit A. The endless member M is imperforate and of a width sub- 110

stantially equal with the space between the side walls 2 of said air chamber or conduit A. The member M is disposed around the drums 3 rotatably supported by the side walls 2 of the chamber of conduit A and interposed therebetween and the outer drum 3 is adjustable longitudinally of the conduit or chamber A as may be necessitated by the requirements of practice. An end portion of 10 the shaft 4 of the inner drum 3 extends exteriorly of the chamber or conduit A and said extended portion has affixed thereto a pulley 5 whereby the member M may be operated with the upper stretch thereof traveling in a direction toward the opening 1 and the ingress end of the conduit or chamber A. Projecting outwardly from the member M, which preferably constitutes a belt, is a plurality of transversely disposed series 15 of teeth or sprigs 6. Adjacent series of the teeth or sprigs 6 are in relatively close proximity to each other and said teeth are disposed on an incline in a direction longitudinally of the member M and in the direction of travel thereof.

Arranged within the induction end of the chamber or conduit A is a substantially horizontally disposed table or apron 7 of a length to slightly overlie the adjacent or 30 inner end portion of the upper stretch of the member M. The table or apron 7, together with the upper stretch of the member M, constitutes the floor of the chamber or conduit A with the upper stretch of the member M operating as a movable portion 35 of said floor.

The cotton and associated matter delivered from a conventional type of boll breaker is blown by a suitable air draft 40 through the air chamber or conduit A above the floor thereof and during which time, the member M is in operation. The upper stretch of the member M moves toward the induction end of the chamber or conduit A 45 and during such movement, the sprigs or teeth 6 effectually pick or separate the cotton from the trash and hulls. The dirt or other comminuted matter entering into the chamber or conduit A in association with 50 the cotton passes out of the eduction end of the chamber or conduit A with the air.

Arranged within the chamber or conduit A above the upper stretch of the member M is a plurality of longitudinally spaced 55 rock arms 8 supported by the side walls 2 of said chamber or conduit and depending from each of said rock arms 8 is a plurality of longitudinally spaced fingers 9. Each of the rock arms 8, together with the depending 60 fingers 9 carried thereby operates as a deflector to force the cotton and the matter associated therewith into contact with the upper stretch of the member M so that the functioning of said member M through the 65 instrumentality of the teeth or sprigs 6

is materially facilitated. The action of these teeth or sprigs 6 is also made more effective by the direction in which the same are inclined. Coacting with each of the rock arms 8 are suitable means, as at 10, whereby 70 the same may be held in different angular adjustments with respect to the upper stretch of the member M and as may be preferred in practice.

Outwardly of the inner drum 3 and supported by the side walls of the conduit or chamber A is a rotary brush 11 rotating from above in a direction toward the member M and which brush, during the operation of the machine, extracts or removes from the 80 teeth or sprigs 6 the cotton carried thereby whereby said cotton is discharged into the housing H through the opening 1. One end portion of the shaft 12 of the rotary brush 11 extends exteriorly of the conduit or chamber A and at the same side as the extended portion of the shaft 4. Fixed to said extended portion of the shaft 12 is a pulley 14, herein disclosed in driving connection with the pulley 5 through the instrumentality of a cross belt 15. The extended portion of the shaft 12 has also affixed thereto a second pulley 16 adapted to be operatively engaged, preferably through the medium of 90 a belt, with a suitable source of power. 95

The rotary brush 11 is positioned below the table or apron 7 and is contained within a casing 17 provided in its lower portion with a suitable opening to afford communication with the opening 1 and in its forward portion with a suitable opening 18 through which the cotton and the like passes when taken from the member M by the rotary brush 11. The upper and lower marginal portions of the casing 17 defining the 100 opening 18 are continued by the extensions 19. The upper extension 19 is continued to the under surface of the table or apron 7 and conforms to the adjacent portion of the member M passing around the drum 3 while 110 the lower extension 19 also conforms to the adjacent curvature of the member M and leads to the closed bottom 20 of the chamber or conduit A.

Interposed between the upper portions of 115 the side members 21 of the housing H and at the inner edge of the opening 1 is a plate or wall 22 whereby a receiving hopper R is provided in the upper portion of the housing H and into which the cotton is delivered 120 from the member M. Disposed transversely of the housing H through the upper portion of the hopper R and rotatably supported by the side walls 21 of the housing H are the shafts 23 to each of which is fixed within 125 the hopper a fluted feed roller 24 adapted to rotate from above in a direction one to the other and which rollers operate to force the material delivered within the hopper R downwardly thereof.

The lower portion of the hopper R is partially closed by a rotary beater 25 carried by a shaft 26 supported by the side walls 21 of the housing H and which beater rotates inwardly from above. Positioned directly below the beater 25 and in close proximity thereto is a second rotary beater 27 carried by a shaft 28 supported by the side walls 21 of the housing H. Below the beater 27 and positioned slightly inward thereof is a third rotary beater 29 carried by a shaft 30 also rotatably supported by the side walls of the housing H. The end wall 31 of the housing H adjacent the beaters 25, 27 and 29 is provided with the concaves 32 into which each of said beaters partially extend. 33 denotes a drum of relatively large radius interposed between the side walls 21 of the housing H and fixed to a shaft 34 supported by said side wall. A drum 33 is positioned inwardly of and entirely to one side of the hopper R and also arranged therebelow. Said drum 33 when in operation, rotates from below in a direction away from the beaters 25, 27 and 29 while said beaters all rotate in the same direction and in a direction from above toward the drum 33.

Extending outwardly from the periphery of the drum 33 are the teeth or sprigs 35, said teeth being disposed on an incline in the direction of rotation of said drum 33. As the cotton and associated matter is forced downwardly through the hopper R, the upper rotary beater 25 forces such material toward the drum 33 and in a downward direction. This action is also repeated by the beaters 27 and 29. As the drum 33 rotates the teeth or sprigs 35 carried thereby serve to recover or separate the cotton and lint from the hulls, trash and the like and which separated hulls and kindred foreign matter is discharged upon the chute 36 and delivered thereby to a suitable conveyer for carrying off said matter.

50 Rotatably supported by the side walls 21 of the housing H at a point above the shaft 34 and to the side of the drum 33 remote from the beaters 25, 27 and 29 is a rotary brush 37 which rotates from above in a direction toward the drum 33 and operates to disengage from the teeth or sprigs 35 the cotton or lint carried thereby. As the cotton or lint is freed from said teeth or sprigs 35, the same is thrown by the rotary brush 37 upon the chute 38 and which cotton or lint is then delivered to a gin.

55 The brush 37 is fixed to a shaft 39 having an end portion extending exteriorly of the housing H and to said extended portion is secured a pulley 40. Directed around the pulley 40 is a belt B which also extends under and engages a pulley 41 fixed to the extended portion of a shaft 42, rotatably supported by the side walls 21 of the housing H. The shaft 42 is positioned above

the drum 33 at a point in close proximity to the plate or wall 22 and above the lower or free margin thereof. Fixed to the shaft 42 between the side walls 21 is a fluted or ribbed roller 43, rotating from above in a direction toward the drum 33 and which serves to prevent hulls, trash or the like to pass upwardly and over the drum 33.

70 The belt B passes from the pulley 41 to and over a pulley 44 carried by the extended portion of the adjacent shaft 23 and from said pulley 44, said belt passes under a pulley 45 carried by the extended portion of the second shaft 23. From the pulley 45 the belt B extends to a suitable source of power.

75 The belt B from the pulley 40 and to a pulley 46 secured to the extended portion of the shaft 34 passes over and around said pulley. From the pulley 46, the belt B passes under an idle pulley 47 rotatably supported by the adjacent side walls 21 of the housing H and from the pulley 47 over a pulley 49 fixed to the extended portion of the shaft 30. From the pulley 49, the belt B extends under and around an idle pulley 50 rotatably supported by the adjacent side wall 21 of the housing H and then inwardly of and in driving contact with the pulleys 51 and 52 carried by the extended portions of the shafts 28 and 26 respectively. The belt B also passes over the pulley 52 at which point it leads to the source of power. By this particular arrangement of the belt B, the various rotary elements are caused to 80 85 90 95 100 105 110 115 120 125 130

revolve in the desired directions. From the foregoing description, it is thought to be obvious that a machine constructed in accordance with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice except as hereinafter claimed.

I claim:—

1. A machine of the class described including an air conduit, an endless member having a stretch constituting a portion of the floor of said conduit, said stretch of the endless member traveling in a direction toward the induction end of the conduit, outstanding teeth carried by said endless member, and deflecting members arranged within the air conduit above the endless member for forcing the material passing through the air conduit toward the endless member, said deflecting members being angularly adjustable with respect to the endless member.
2. A machine of the class described in-

cluding an air conduit, an endless member having a stretch constituting a portion of the floor of said conduit, said stretch of the endless member traveling in a direction toward the induction end of the conduit, outstanding teeth carried by said endless member, and deflecting members arranged within the air conduit above the endless member for forcing the material passing through the air conduit toward the endless member, said deflecting members being angularly adjustable with respect to the endless member and in a direction longitudinally of said member.

3. A machine of the class described comprising a rotary member, teeth extending outwardly from the periphery of said member, rotary beaters arranged at one side of the rotary member for forcing the material to be treated toward the rotary member, means for freeing from the teeth of the rotary member the material carried thereby, and a fluted rotary member positioned above the first named rotary member and rotating in the same direction as the first named rotary member.

4. A machine of the class described comprising a rotary member, teeth extending outwardly from the periphery of said member, rotary beaters arranged at one side of the rotary member for forcing the material to be treated toward the rotary member, means for freeing from the teeth of the rotary member the material carried thereby,

and a fluted rotary member positioned above the first named rotary member and rotating in the same direction as the first named rotary member.

5. A machine of the class described comprising a rotary member, teeth extending outwardly from the periphery of said member, rotary beaters arranged at one side of the rotary member for forcing the material to be treated toward the rotary member, means for freeing from the teeth of the rotary member the material carried thereby, and feeding rolls positioned above the rotary beaters for forcing the material in a direction toward said beaters and the rotary member.

6. A machine of the class described comprising a rotary member, teeth extending outwardly from the periphery of said member, beaters arranged at one side of the rotary member for forcing the material to be treated toward the rotary member, means for freeing from the teeth of the rotary member the material carried thereby, and a fluted rotary member positioned above the first named rotary member and rotating in the same direction as the first named rotary member.

In testimony whereof I hereunto affix my signature.

HORACE E. WALKER.
